UNITED STATES PATENT OFFICE

149,451

DESIGN FOR A RACING SULKY

Robert A. Shuttleworth, Buffalo, N. Y.

Application December 2, 1946, Serial No. 135,215

Term of patent 3½ years

(Cl. D14—3)

To all whom it may concern:

Be it known that I, Robert A. Shuttleworth, a citizen of the United States, residing at Buffalo, in the county of Erie and State of New York, have invented a new, original, and ornamental Design for a Racing Sulky, of which the following is a specification, reference being had to the accompanying drawings, forming part thereof.

Fig. 1 is a perspective view of a racing sulky, showing my new design.

Fig. 2 is a side view of the same.

Fig. 3 is a top plan view thereof.

Fig. 4 is a rear elevational view of the same.

The characteristic features of my design reside

in the portions shown by means of full lines in the drawings.

I claim:

The ornamental design for a racing sulky, substantially as shown and described.

ROBERT A. SHUTTLEWORTH.
